ICE BUCKET

Bennett H. Stayman, 23 Ascenta Terrace,
West Newton, Mass.

Filed Oct. 7, 1963, Ser. No. 76,884

Term of patent 14 years

(Cl. D44—15)

FIG.1

FIG.2

FIG. 3

FIG. 4

FIG. 1 is a perspective view of an ice bucket showing my new design;

FIG. 2 is a top plan view on a slightly reduced scale;

FIG. 3 is a front elevational view on the view on the same scale as FIG. 1; and

FIG. 4 is a bottom plan view thereof.

I claim:

The ornamental design for an ice bucket, as shown.
